THREAD PARTING AND CLAMPING MECHANISM.

1,352,083.

Specification of Letters Patent.

Patented Sept. 7, 1920.

Application filed March 8, 1918. Serial No. 221,110.

To all whom it may concern:

Be it known that I, JONAS NORTHRUP, a citizen of the United States, residing at Hopedale, in the county of Worcester and State of Massachusetts, have invented certain new and useful Improvements in Thread Parting and Clamping Mechanism; and I do hereby declare the following to be a full, clear, and exact description of the invention, such as will enable others skilled in the art to which it appertains to make and use the same:

The present invention relates to an improvement in thread parting and clamping mechanisms for weft-replenishing looms.

In filling feeler controlled, weft replenishing looms, wherein the weft replenishing mechanism is located on one side of the loom and the filling feeler mechanism is located on the opposite side of the loom, the filling detector mechanism for detecting the presence or absence of filling in the shed is usually located at the filling feeler side of the loom. This arrangement is not satisfactory, because if the filling completely unwinds from the bobbin while the shuttle is traveling toward the replenishing side of the loom after the indication of critical exhaustion of the filling, a mispick will result. If the filling detector is located on the replenishing side of the loom, the absence of the filling caused by its complete exhaustion from the bobbin will be detected and the loom stopped so that the short weft can be removed by the operator. But, when the filling fork of the detector mechanism is located beside the replenishing mechanism, the absence or presence of filling in the shed for the first few beats after replenishment cannot always be detected because of the presence of the outgoing or incoming filling ends. It is accordingly proposed in the present invention to produce an improved thread parting and clamping mechanism having provision for drawing the outgoing and incoming filling ends toward the breast beam into such position that they will be out of the range of action of a filling fork located at the replenishing side of the loom. By the provision of this improved thread parting and clamping mechanism the filling detector mechanism may be located and successfully operated on the replenishing side of the loom.

The thread parting and clamping mecha-

nism of the present invention is particularly pointed out in the appended claims, and the preferred specific embodiment of the invention is described in the following specification and is illustrated in the accompanying drawings, in which Figure 1 is a plan-view of a part of the replenishing end of a weft replenishing loom, showing the application thereto of the improved thread parting and clamping mechanism and its position relatively to the loom temple and the filling detector mechanism; Fig. 2 is a side elevation of the thread parting and clamping mechanism, with the associated parts of the loom necessary for its operation; Fig. 3 is a side elevation of the thread parting and clamping mechanism, showing the positions assumed by the parts on the indication of predetermined exhaustion of the filling; Fig. 4 is a view similar to Fig. 3, showing the positions assumed by the parts of the parting and clamping mechanism on the backward beat of the lay after replenishment; and Fig. 5 is a section taken on the line 5—5 of Fig. 4.

The improved thread parting and clamping mechanism is shown in the illustrated embodiment of the invention as applied to the replenishing end of a feeler loom, in which the replenishing mechanism is located at one side of the loom and the filling feeler mechanism at the opposite side. Both these mechanisms may be of any usual or preferred construction. The weft replenishing mechanism is in part indicated by the hopper plate 10, which is supported on a bracket 11 secured to the breast beam 12. The replenishing mechanism is connected with the filling feeler mechanism (not shown in the drawings) by a rock or change shaft 14 which is mounted on the front of the breast beam and extends transversely thereof. A hopper arm 15 is secured to the change shaft and is yieldingly connected with an arm 16 extending upwardly from a hub 17 loosely mounted on a stud 19 fastened in the hopper plate 10. The change shaft 14 and its associated parts, by which the replenishing operation is initiated, are known as the loom controlling devices. Depending downwardly from the hub 17 is a latch lifting arm 20 having a slot at its lower end adapted to receive a pin 21 projecting laterally from the latch 22, which is pivotally connected on the lower end of an arm 23.

extending downwardly from the hub 26 of the transerrer hammer 27, of which only a portion is shown in the drawings. When the filling feeler mechanism indicates predetermined exhaustion of the filling, the change shaft 14 is oscillated in a direction to swing the hopper arm 15 outwardly, that is, to the right, viewing Fig. 2, thereby acting on the arm 20 to present the latch 22 in the path of the bunter 28 secured to the front of the lay 24. The indication of predetermined exhaustion of filling takes place on one beat-up of the lay, and the replenishing operation takes place on the succeeding beat-up of the lay. Cooperating with these parts is a shuttle feeler 29 pivoted on a stud 30 secured in the hopper plate 10. The shuttle feeler 29, in addition to its usual shuttle feeling function, constitutes a part of the thread parting and clamping mechanism of the present invention, and for the latter purpose its connection with the loom controlling devices is novel with the present invention. It performs its shuttle feeling function, however, in the usual manner, that is to say, when the filling feeler mechanism indicates predetermined exhaustion of filling and thereby operates to swing the hopper arm 15 outwardly, the shuttle feeler is thrown into shuttle feeling position, so that, if on the next succeeding or replenishing beat-up of the lay the shuttle 31 is improperly boxed, it will strike the lower end of the shuttle feeler and push it toward the breast beam, thereby operating to drop the latch 22 out of the path of the bunter 28. The manner in which this function is performed will be more fully described in the particular description of the construction of the thread parting and clamping mechanism.

The filling detector mechanism for determining the presence or absence of filling in the shed is located at the replenishing side 45 of the loom between the replenishing mechanism and the cloth selvage. The detector mechanism is indicated generally by the reference character 33, and comprises a filling fork 34 pivoted on the rear end of a detector slide 35, the forward end of which engages an arm 36 secured to and extending upwardly from a hollow stop shaft 37 connected at the other end of the loom with the loom stopping devices. The detector slide 35 is loosely supported in a guideway 38 fastened to the breast beam 12. The filling fork 34 is provided with a tail or bail 39 which, when filling is absent and the fork is not tilted, cooperates with a hook 40 of the weft hammer 41 to give the slide 35 a forward movement to oscillate the arm 36 and the stop shaft 37 to stop the loom. For the purposes of the present invention the tines of the filling fork 34 are located 65 between the fork pivot 43 and the breast

beam so that the fork will have an immediate rising action when the tines are pressed by a filling end on their rear side. The loom temple is indicated at 45 and is provided with a thread cutter 46 which operates to part the outgoing and incoming filling ends at the cloth selvage. The foregoing parts, with the exception of the shuttle feeler, are all constructed and operate in a manner familiar to those skilled in the art. 75

The improved thread parting and clamping mechanism operates first to part and clamp the outgoing filling end and hold it in a position out of the range of action of the filling fork, and then to clamp but not sever the incoming filling end and hold it also out of the range of action of the filling fork. The parting and clamping of the outgoing filling end occurs on the replenishing beat-up of the lay, and the clamping of the incoming filling end occurs on the succeeding beat-up of the lay. During each operation, the respective filling ends are engaged and drawn forward toward the breast beam, and in so doing they first come into engagement with the tines of the filling fork, which is so constructed that the filling easily tilts the fork and passes by the tines, permitting the filling fork to return immediately into filling detecting position. As a result of 95 this operation the function of the filling fork in detecting the absence or presence of the filling in the shed is not interfered with by either the outgoing or the incoming filling ends. The incoming filling end is permitted 100 to be drawn forward toward the breast beam without liability of breakage, because the act of pulling this filling end toward the breast beam is performed while the shuttle 105 is being picked from the replenishing side of the loom immediately following the replenishing operation and before the closing of the warp threads for the next shedding.

The parting and clamping of the outgoing filling end is performed by a thread 110 parting and clamping device, comprising a fixed parting and clamping blade 50, a movable parting blade 51, and a movable clamping blade 52. The fixed parting and clamping blade extends rearwardly toward the lay from a hub fastened to the stud 19. The movable parting and clamping blades are pivoted on the pin 58 passed through the fixed blade. A spring 54 surrounding the pin 58 serves to yieldingly and frictionally 115 hold the movable blades in contact with the fixed blade, so that the parting and clamping operation will be effectively performed and so that when the blades are moved into open position, they will remain in that position. The movable blades are connected together by a pin 55 so as to move in unison. The opening of the movable blades is performed by a T-shaped piece 57 pivotally connected at 58 to a bracket 59 secured to the 120

130

upper end of the hopper arm 15. Depending from the cross-bar of the T-shaped piece 57 is a leg 60 having a projecting pin 62 which normally engages the rear side of the 5 upwardly extending part 63 of the movable blades. When the hopper arm 15 is moved outwardly on the indication of predetermined exhaustion of the filling, it carries the T-shaped piece 57 with it, thereby forcing 10 the pin 62 against the movable blades and oscillating them on the pin 53 into open position, as shown in Fig. 3. The thread parting and clamping means is now in position to receive the outgoing filling end. It will 15 be observed by reference to Figs. 1 and 2 that the thread parting and clamping means is beyond the limit of the forward movement of the lay, and that, therefore, the outgoing filling end must be drawn between 20 the parting and clamping blades. The shuttle feeler performs this function, the lower end thereof being constructed and arranged to act as a thread hook. The shuttle feeler is connected with the forward end of the 25 T-piece 57 by means of a spring 65 fastened to the piece 57, and a strap 66 fastened to the hub of the shuttle feeler. The shuttle feeler is held in its normal position, as shown in Figs. 1 and 2, by a cam piece 68 30 pivotally mounted on a pin 69 passed through the upper end of the arm 16. The forward end of the cam piece 68 is provided with an upward extension 70, the upper end of which is connected by a spring 71 with 35 the bracket 59 fastened on the hopper arm 15. The cam piece 68 is provided with two recesses 72 and 73 which are adapted to receive a pin 74 projecting laterally from the shuttle feeler. When the shuttle feeler is in 40 normal position, the pin 74 is received in the recess 72, as shown in Fig. 2, and when the shuttle feeler is in shuttle feeling position, or is in position preliminary to engaging the incoming filling end, the pin 74 is received in the recess 73. The cam piece 68 is 45 provided with a surface 75 which is adapted, when the hopper arm 15 moves outwardly, to come into contact with the hub 17. While the cam piece 68 is in this position, with the shuttle feeler in shuttle feeling position, and a shuttle is improperly boxed on the replenishing beat-up of the lay and therefore strikes the lower end of the shuttle feeler, the pressure of the shuttle 50 feeler against the rear end of the cam piece 68 serves to oscillate the arm 16 and the parts connected with it about the stud 19 as a fulcrum to depress the latch 22 out of the path of the bunter 28. It is thus seen that 55 the shuttle feeler performs its usual function in preventing the weft replenishing operation, in the event of an improperly boxed shuttle on the replenishing beat-up of the lay.

60 When the shuttle feeler has been thrown into its shuttle feeling position on an operation of the loom controlling devices, as shown in Fig. 3, it is in the path of a bunter 76 secured to the top shuttle box plate 77, so that, as the lay moves forward on the 70 succeeding beat-up, the bunter 76 strikes the shuttle feeler and forces it forward. It will be observed that the lower end of the shuttle feeler being constructed and arranged to act as a thread hook, as the shuttle feeler 75 is forced forward by the bunter 76 it engages the strand of filling extending from the selvage to the replenishing mechanism and draws it toward the breast beam. If this strand of filling is the outgoing filling 80 end, that is, if it is the strand of filling extending from the selvage to the bobbin about to be ejected from the shuttle, the filling is drawn between the open parting and clamping jaws. Then, as the shuttle feeler 85 continues its forward movement under pressure of the bunter 76, the part 78 on the lower end of the feeler presses on the surface 79 of the movable thread parting and clamping members and closes these members upon the filling, thereby severing the filling by the action of the blade 51 on the blade 50 and clamping the severed filling 90 end by the action of the blade 52 on the opposite side of the blade 50. It will be observed in this connection that the movable parting blade 51 is on the side of the blade 50 away from the selvage, and that the clamping blade 52 is between the blade 50 and the selvage so as to hold the piece of 95 filling extending from the selvage to the clamping means. As the outgoing filling end is being drawn toward the breast beam by the shuttle feeler, it first encounters the tines of the filling fork, and inasmuch as 100 these tines are positioned with respect to the fork pivot 43 as described, the filling is easily drawn past the tines in tilting them, thus permitting them to return immediately 105 into their operative position. After the outgoing filling end has been parted and clamped by the parting and clamping means, it is held in the position with respect to the filling fork, as shown in Fig. 1, in which the reference character 110 80 indicates the outgoing filling end. The outgoing filling end will be held in this position until it is severed at the selvage by the temple 115 thread cutter 46.

120 After the shuttle feeler has been moved forward by the bunter 76 on the replenishing beat-up to deliver the outgoing filling end to the parting and clamping means, it again moves rearwardly so as to be in position to engage the incoming filling end and 125 draw it forward on the succeeding beat-up of the lay. The shuttle feeler is moved rearwardly for the second time by the coöperation of the spring 65 and the cam piece 68. When the shuttle feeler was moved forward 130

on the replenishing beat-up by the bunter 76, the pin 74 was forced out of the recess 73 and traveled up along the surface 81 of the cam piece. This movement of the pin 74 relatively to the cam piece 68 of course oscillated the parts connected with the arm 16 about the stud 19 as a center, but inasmuch as at this time the bunter 28 had already engaged the latch 22, this movement of the parts connected with the arm 16 about the stud 19 had no operative effect. These parts are so constructed as to provide for this relative inoperative movement. As the lay beats backward after the replenishing operation, the hopper arm, as usual, moves rearwardly to its normal position, thereby returning the arm 16 and the parts connected with it to their normal position. But inasmuch as the pin 74 at this time is on the rear side of the point 82 on the cam piece 68, the spring 71 operates to force the rear end of the cam piece 68 upwardly and the shuttle feeler rearwardly. This movement is assisted by the action of the spring 65. The pin 74 is thereby again received in the recess 73, and so the shuttle feeler is held in rearward position. When the lay has reached the limit of its rearward movement and the hopper arm 15 has returned to its normal position, the parts of the thread parting and clamping mechanism are in the positions shown in Fig. 4. With the shuttle feeler in the position shown in this figure, its shuttle feeling end is above the path of motion of the shuttle, when the shuttle is boxed at this end of the loom and the lay moves forward; consequently, it does not perform its shuttle feeling function on this beat-up, nor is this required. It is, however, in such position that as the lay moves forward on the beat-up following the replenishing operation, the bunter 76 will strike it and move it toward the breast beam. During this forward movement, its lower end will engage the incoming filling end and pull it toward the breast beam. No provision is made for severing the incoming filling end, except at the selvage by the temple thread cutter 46. The incoming filling end is thereafter held in the position shown in Fig. 1, (in which the incoming filling end is indicated by the reference character 85) by the shuttle feeler which is now in its normal position with the pin 74 in the recess 72, having been forced almost to that position by the bunter 76. The action of the cam piece 68 under the influence of the spring 71 completes the reception of the pin 74 in the recess 72, so as to move the shuttle feeler toward the breast beam a slight distance beyond the limit of the forward movement of the bunter 76. As an aid in assisting the thread hook functions of the shuttle feeler, the lower end thereof is provided with a piece of felt 86, which prevents the chafing and consequent breaking of the filling end and also assists in holding the incoming filling end firmly until it is severed at the selvage. In order that the incoming filling end may be drawn out of the replenishing shuttle box, the front wall 87 thereof is slotted at 88. The incoming filling end tilts and passes under the tines of the filling fork in the same manner in which the outgoing filling end tilts and passes under the filling fork tines. It will be recognized that while the shuttle feeler is drawing forward the incoming filling end, the shuttle is traveling through the shed paying out the filling. There is therefore no liability of breaking the incoming filling end in drawing it toward the breast beam.

The mode of operation of the improved thread parting and clamping mechanism will be briefly recapitulated: During the weaving operations of the loom the parts of the thread parting and clamping mechanism are in the positions shown in Figs. 1 and 2. It is assumed that there has been an indication of predetermined exhaustion of filling in the active shuttle and that, as usual, through the operation of the loom controlling devices the change shaft 14 has been oscillated to swing the hopper arm 15 outwardly. The outward movement of the hopper arm pulls the T-piece 57 forward, thereby opening the thread parting and clamping jaws and swinging the shuttle feeler into shuttle feeling position. While these movements are taking place, the shuttle has been picked to the replenishing end of the loom and the lay begins its replenishing beat-up. The flight of the shuttle to the replenishing side of the loom left the outgoing filling end extending from the selvage to the weft replenishing mechanism, so that, as the lay now beats up and the bunter 76 strikes the shuttle feeler and pushes it forward toward the breast beam, the outgoing filling end is engaged by the shuttle feeler and delivered between the open jaws of the parting and clamping blades. Almost simultaneously therewith, the movable blades are closed upon the filling, which is then parted and clamped as shown in Fig. 1, by the pressure of the shuttle feeler against the movable blades. During this beat-up of the lay the replenishing operation has taken place, as usual, and on the succeeding backward beat of the lay the spring 65 and the cam piece 68 in co-operation move the shuttle feeler into the position shown in Fig. 4. By the time the shuttle feeler has reached this position, which is its position preliminary to engaging the incoming filling end, the shuttle has been picked away from the replenishing mechanism leaving the incoming filling end extending from the hopper stud 89 to the cloth selvage and the lay then beats up again. On this

beat-up the bunter 76 again strikes the shuttle feeler and forces it forward into its normal position, where it is held by the cam piece 68. During this beat-up of the lay, 5 the shuttle feeler has drawn the incoming filling end toward the breast beam, where it is held by the shuttle feeler, as shown in the position in Fig. 1. Both the outgoing and incoming filling ends are thus in a position 10 out of the range of action of the filling fork.

The thread parting and clamping mechanism of the present invention has been shown and described as applied to a filling 15 feeler controlled, weft replenishing loom. It will be understood that the invention is not limited to application to feeler looms, but that it may be applied to filling detector controlled, weft replenishing looms. When 20 the mechanism is applied to this latter type of loom, it is obvious that the thread parting and clamping blades may be removed, because there is no outgoing filling end to part and clamp. The incoming filling end, 25 however, would be operated upon in exactly the same way as above described. It will furthermore be recognized that the invention may be embodied in other forms than that shown and described, and yet be within 30 the scope of the following claims.

Having thus described the invention, what I claim is:

1. A loom having, in combination, weft replenishing mechanism, loom controlling 35 devices, a filling fork located beside the replenishing mechanism, a fixed parting and clamping blade, movable parting and clamping blades normally closed, a shuttle feeler constructed to act as a thread hook to draw 40 the outgoing and incoming filling ends toward the breast beam, means connected with the loom controlling devices to open the movable parting and clamping blades and to swing the shuttle feeler into shuttle feeler 45 and filling and engaging position, a bunter on the lay arranged to push the shuttle feeler forward so that it may deliver the outgoing filling end to and close the movable parting and clamping blades 50 to sever and hold the filling end.

2. A loom having, in combination, weft replenishing mechanism, loom controlling devices, a filling fork located beside the replenishing mechanism, and a thread parting 55 and clamping mechanism located between the filling fork and the replenishing mechanism, having provision for parting the outgoing filling end and for holding both the outgoing and incoming filling ends 60 out of the range of action of the filling fork so that the action of the filling fork in detecting the absence or presence of filling in the shed is not interfered with by the outgoing and incoming filling ends.

3. A loom having, in combination, weft 65 replenishing mechanism, loom controlling devices, a filling fork located on the replenishing side of the loom, and a thread parting and clamping mechanism comprising thread parting and clamping means and a 70 shuttle feeler constructed to act as a thread hook, said parting and clamping means and shuttle feeler being actuated in one direction by the loom controlling devices and in the opposite direction by the lay to hold the 75 outgoing and incoming filling ends out of the range of action of the filling fork.

4. A loom having, in combination, weft replenishing mechanism, loom controlling 80 devices, a filling fork located on the replenishing side of the loom, means for parting the outgoing filling end and clamping it in a position out of the range of action of the filling fork, and means for delivering the outgoing filling end to the parting 85 and clamping means on the replenishing beat-up of the lay, and for drawing the incoming filling end to a position out of the range of action of the filling fork on the succeeding beat-up of the lay and thereafter holding it in that position.

5. A loom having, in combination, weft replenishing mechanism, loom controlling devices, a filling fork located on the replenishing side of the loom, and means having provision on two successive beat-ups of the lay to secure the outgoing filling end on one beat-up and the incoming filling end on the next beat-up, and hold them in such 95 position that the filling fork may properly 100 perform its filling detecting function.

6. A loom having, in combination, weft replenishing mechanism, loom controlling devices, a filling fork located on the replenishing side of the loom, a shuttle feeler 105 constructed and arranged to act as a thread hook in addition to its shuttle feeling functions and as such thread hook being adapted to draw both the outgoing and incoming filling ends to a position out of the range 110 of action of the filling fork, and means for actuating the shuttle feeler.

7. A loom having, in combination, weft replenishing mechanism, loom controlling 115 devices, a filling fork, thread parting and clamping means, a shuttle feeler arranged to deliver the outgoing filling end to the parting and clamping means and to hold the incoming filling end in a position relatively near the breast beam, and means including the lay and the loom controlling 120 devices for actuating the shuttle feeler and the thread parting and clamping means.

8. A loom having, in combination, weft replenishing mechanism, loom controlling devices, a fixed thread parting and clamping blade mounted on the breast beam, movable parting and clamping blades normally 125

- closed, means connected with the loom controlling devices for opening the movable blades, means arranged to deliver the outgoing filling end between the fixed and movable blades and thereafter close the movable blades upon the filling, and means for actuating the last-named means.
9. A loom having, in combination, weft replenishing mechanism, loom controlling devices, a fixed thread parting and clamping blade, movable parting and clamping blades, means for opening the blades, and a lay-actuated shuttle feeler arranged to deliver the outgoing filling end between the fixed and movable blades, and thereafter close the movable blades upon the filling.
10. A loom having, in combination, weft replenishing mechanism, loom controlling devices, a shuttle feeler, means connected with the loom controlling devices to move the shuttle feeler into shuttle feeling position for the replenishing beat-up of the lay, means for moving the shuttle feeler into incoming filling end engaging position for the beat-up of the lay following replenishment, and a bunter on the lay for moving the shuttle feeler toward the breast beam, said shuttle feeler having provision for engaging and drawing the outgoing and incoming filling ends with it as it is moved toward the breast beam.
11. A loom having, in combination, weft replenishing mechanism, loom controlling devices, a filling fork located on the replenishing side of the loom, a thread hook operating on the replenishing beat-up of the lay to draw the outgoing filling end out of the range of action of the filling fork and operating on the next succeeding beat-up of the lay to draw the incoming filling end out of the range of action of the filling fork, and means for actuating the thread hook.
12. A loom having, in combination, weft replenishing mechanism, loom controlling devices, a filling fork on the replenishing side of the loom, and means for engaging and pulling the filling extending from the selvage to the weft replenishing mechanism out of the range of action of the filling fork on the replenishing beat-up of the lay and 50 on the next succeeding beat-up.
13. A loom having, in combination, weft replenishing mechanism, loom controlling devices, a filling fork located on the replenishing side of the loom, and means for drawing the outgoing filling end to a position out of the range of action of the filling fork and holding it in that position so that it will not interfere with the detecting action of the fork.
14. A loom having, in combination, weft replenishing mechanism, loom controlling devices, a shuttle feeler constructed to engage and draw with it the filling as it is moved toward the breast beam, means connected with the loom controlling devices to move the shuttle feeler into shuttle feeling position for the replenishing beat-up of the lay, means for moving the shuttle feeler into incoming filling end engaging position 70 for the beat-up of the lay following replenishment, and means for moving the shuttle feeler toward the breast beam.
15. A loom having, in combination, weft replenishing mechanism, loom controlling devices, a filling fork located on the replenishing side of the loom, and means for drawing the incoming filling end to a position out of the range of action of the filling fork and holding it in that position so that it 80 will not interfere with the detecting action of the fork.
16. A loom having, in combination, a weft replenishing mechanism, loom controlling devices, a filling fork, and means for drawing the incoming filling thread intact out of its normal position, to prevent its interference with the detecting action of the fork.
17. A loom having, in combination, a weft replenishing mechanism, loom controlling devices, a filling fork, and means for drawing the incoming filling thread intact out of its normal position on the first rearward beat of the lay after replenishment, to prevent its interference with the detecting action of the fork.

JONAS NORTHRUP.
